UNITED STATES PATENT OFFICE.

THOMAS W. SYMINGTON AND CHARLES E. KLINK, OF DETROIT, MICHIGAN.

DESIGN FOR A RING.

Application filed April 7, 1924. Serial No. 9,187. Term of patent 7 years.

To all whom it may concern:

Be it known that we, THOMAS W. SYMINGTON and CHARLES E. KLINK, both citizens of the United States, residing at Detroit, in the county of Wayne and State of Michigan, have invented a new, original, and ornamental Design for Rings, of which the following is a specification, reference being had to the accompanying drawing, forming part thereof.

In the drawing,

Fig. 1 is an enlarged perspective view of a ring embodying our new design.

Fig. 2 is a transverse section of the ring.
We claim:—

The ornamental design for a ring, as shown.

THOMAS W. SYMINGTON.
CHARLES E. KLINK.
